UNITED STATES PATENT OFFICE.

G. HENRY HUISKAMP, OF TROY, NEW YORK.

METALLIC BRIDGE FOR PIANOFORTES.

Specification of Letters Patent No. 17,838, dated July 21, 1857.

To all whom it may concern:

Be it known that I, G. HENRY HUISKAMP, of the city of Troy, in the State of New York, have invented some new and 5 useful Improvements in Harmonic Metallic Bridges for Pianofortes, of which the following is a full, clear, and exact description, reference being had to the accompanying drawings, making part thereof, in which—
10 Figure 1 is a plan. Fig. 2 a vertical section taken at the line A a of Fig. 1, and Figs. 3, 4, and 5 vertical sections of portions of the improvement.

The same letters indicate like parts in all 15 the figures.

To insure pure tones in pianofortes it is necessary that the strings should be held firmly in contact with the bridges at the two points which determine the vibrating length 20 of the strings that the points of contact should be such as to present a sufficient resistance to prevent the vibration from extending on to or beyond the bearing points and to resist the strokes of the hammer, for 25 it is well known that the quality of the tones is much affected by any imperfection at the bearing or supporting points. And finally it is important that the bridges or supporting surfaces should have no vibration within 30 themselves although the sounding board bridge should communicate the vibrations of the strings to the sounding board on which it rests. In view of these results the bridges of pianofortes have been so constructed as to form bearing surfaces both 35 above and below the strings on their passage to the pegs and pins. In this way by very slight deflections from a straight line the strings are firmly held at the points which 40 determine the lengths of vibration for the various tones and without reference to the position of the strings on the pegs or pins while at the same time the bearing points, where the vibrations terminate are placed 45 above to present resistance to the upward stroke of the hammers and the strokes and vibrations are prevented from affecting either the bridge or the strings beyond the points of support.

50 In the accompanying drawings *a a* represent the frame of the piano which may be of any suitable construction and *b b* the metal frame such as is usually employed. The bridge *i* with its rest *c* is attached to the said iron frame in the manner herein-after specified and between this bridge and

its rest a series of perforations or holes *d* are made in the process of casting through which the strings pass from the tuning pins *e* to the pegs *f*, thus passing over and resting 60 on the surface of the rest *c* and passing and bearing under the lower surface of the bridge *i*. In this way is formed a series of perforations or holes *d* one for the strings of each note, the bridge *i* being connected with 65 the rest *c* by braces *j*, one between the strings of each note and parallel or nearly so with the strings when distended.

It is manifest that when the string is drawn tightly against the lower surface of 70 the bridge and compelled to slide along it in the process of tuning, a great degree of friction will be produced interfering with the nice adjustment of the string and often causing it to break at that point. To remedy this difficulty as far as practicable I cast the lower surface of the bridge *i* with a slight cavity along its entire length in which I insert a rod or wire *k* made of zinc, ivory, 75 wood, brass or other suitable material or 80 composition and secure it to the bridge *i* to hold it in its place. By this device the necessity of fitting and polishing the bearing surface of the bridge *i* is obviated, and while the strength of the cast iron bridge is 85 retained the bearing is upon a material that produces less friction than would take place between steel on iron, and what is of still greater importance the bearing upon a soft material produces a soft tone without the 90 harsh metallic sound that attends a bearing upon cast iron.

The harmonic bridge *i*, has heretofore been cast in one piece, solid with the frame *b, b*. This renders access to the lower surface difficult either for fitting or repairs and makes it almost impossible to give to it the requisite finish and polish. I have retained the requisite solidity and yet made it detachable by affixing it to the lower plate *C*, with 95 dove-tailed joints. For the form represented in Fig. 3, the bridge *i*, is cast separately in one or more pieces, the bottom face having one or more dove-tailed projections *l*, fitted to mortises of corresponding form in the 100 plate *C*, to receive the projections *l*, the said 105 mortises being wedge formed longitudinally so that after the projections have been inserted in the widest part of the mortises by simply pushing the bridge *i* lengthwise it will 110 be firmly held in place.

In grand piano-fortes I dovetail the bridge

i, i, to the cross bars *l, l*, of the frame *b, b*, as represented in Fig. 5, or to projections cast upon the frame.

The drawing is a cross section through the middle of the bridge *i, i*, when in its place.

I cast the flangers *u, u*, upon the sides of the cross bars *l, l*, and the same have a length equal to the width of the bridge *i, i*, and fill the corresponding mortises cast in the bridge *i, i*. By sliding the latter forward beyond the length of these flanges *u, u*, it may be taken from its place.

I have described these modifications as illustrative of the variations which may be made in the mode of applying my invention. And it may be further mentioned among its advantages that it will enable the manufacturer who may desire to obtain the tone peculiar to any particular metal or composition to substitute such material for the bridge in place of cast-iron. In this way its tone will be much improved.

When the piano is made without an iron frame I construct the bridge as represented at Fig. 4 with two flanges *m* and *n*, by means of which it can be secured by screws to the block *o*, of the wooden frame.

The sounding board bridge *p*, is cast in one piece of metal (or in sections if desired) and secured by screws or otherwise to the wooden bridge. This bridge *p*, is also formed with a series of perforations or holes *q*, made in

the direction of the strings—thus connecting by brace pieces *r*, and making part thereof the bottom supporting surface or rest *s*, thence to the securing pegs *f*, and being slightly deflected from a straight line are sure to be kept in contact with supporting surfaces of the bridge and as there is one upper bar on each side, the tension of the strings will have no tendency to tilt or lift one edge of the bridge from the sounding board as would be the case if but one upper bar were employed.

What I claim as my invention and desire to secure by Letters Patent is—

1. The sounding board bridge cast of metal with bearings above the string one on each side of the bottom support, substantially as, and for the purposes specified.

2. I claim the rod or wire *k*, or its equivalent inserted in the bridge to form its bearing surface for the uses and purposes above set forth.

3. I claim the construction and arrangement of the cast metal bridge *i, i*, in such form that it may be detached and yet firmly held in its place—in the mode above set forth or other form substantially the same.

G. HENRY HULSKAMP.
